(57) **CLAIM**

I claim the ornamental design for interchangeable jewelry, as shown and described.

DESCRIPTION

FIG. 1 is a rear, left and bottom perspective view of interchangeable jewelry showing my new design;

FIG. 2 is a rear elevational view thereof;

FIG. 3 is a front elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a top plan view taken along line 8-8 of FIG. 4;

FIG. 9 is a rear, left and bottom perspective view of a second embodiment of Interchangeable jewelry showing my new design;

FIG. 10 is a rear elevational view thereof;

FIG. 11 is a front elevational view thereof;

FIG. 12 is a left elevational view thereof;

FIG. 13 is a right elevational view thereof;

FIG. 14 is a top plan view thereof;

FIG. 15 is a bottom plan view thereof; and,

FIG. 16 is a top plan view taken along the line 16-16 of FIG. 12.

The broken lines shown in the drawings represent unclaimed portions of the Interchangeable Jewelry and form no part of the claimed design.
